(57) **CLAIM**

The ornamental design for a wind and solar-powered light post, as shown and described.

DESCRIPTION

FIG. 1 is a bottom perspective view of the wind and solar powered light post showing our new design;

FIG. 2 is a side elevation view thereof;

FIG. 3 is an opposite side elevation view thereof;

FIG. 4 is a front elevation view thereof;

FIG. 5 is a rear elevation view thereof;

FIG. 6 is a top plan view thereof; and,

FIG. 7 is a bottom plan view thereof.

The broken lines shown on the drawings depict environment only and form no part of the claimed design.
